HEATER

Allan E. Krausz, Centralia, Ill., assignor to Lear Siegler, Inc., Centralia, Ill., a corporation of Delaware

Filed Nov. 20, 1963, Ser. No. 77,510

Term of patent 14 years

(Cl. D81—19)

FIGURE 1 is a front perspective view of a heater showing my new design;

FIGURE 2 is a top plan view thereof; and

FIGURE 3 is a side elevational view thereof.

The dominant features of my design reside in the portions shown in full lines.

The undisclosed rear is substantially flat and plain except for a conventional draft access opening and draft conduit flange as indicated in broken lines in FIGS. 2 and 3.

I claim:

The ornamental design for a heater, substantially as shown and described.
